US0D1038867S

(12) **United States Design Patent** (10) **Patent No.:** **US D1,038,867 S**
(45) **Date of Patent:** **** Aug. 13, 2024**

(54) **BOX MOD BATTERY**

(71) Applicant: **Shenzhen Weipufu Electronic Technology Co., Ltd.**, Guangdong (CN)

(72) Inventor: **Xiang Zou**, Hubei (CN)

(**) Term: **15 Years**

(21) Appl. No.: **29/862,422**

(22) Filed: **Dec. 8, 2022**

(30) **Foreign Application Priority Data**

Jun. 15, 2022 (CN) 202230367128.7
(51) **LOC (14) Cl.** **13-02**
(52) **U.S. Cl.**
USPC **D13/103**
(58) **Field of Classification Search**
USPC D13/102–106, 110, 118, 119, 184, 199; D14/253, 432, 434
CPC H01M 6/00; H01M 6/14; H01M 6/10; H01M 10/52

(57) **CLAIM**

The ornamental design for a box mod battery, as shown and described.

DESCRIPTION

FIG. 1 is a perspective view of a box mod battery showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings represent portions of the Box Mod Battery that form no part of the claimed design.

1 Claim, 8 Drawing Sheets
